UNITED STATES PATENT OFFICE.

EDWIN T. GREENFIELD, OF KIAMESHA, NEW YORK.

HOSE.

979,759.

Specification of Letters Patent. Patented Dec. 27, 1910.

Application filed January 20, 1908. Serial No. 411,582.

To all whom it may concern:

Be it known that I, EDWIN T. GREENFIELD, a citizen of the United States, residing at Kiamesha, in the county of Sullivan 5 and State of New York, have invented certain new and useful Improvements in Hose, of which the following is a specification.

This invention relates to metallic hose so constructed as to be capable of flexure in 10 any direction, the hose being adapted for use in carrying a fluid such as steam or compressed air.

The invention is applicable particularly to flexible metallic hose for use as end-connectors for the train-pipes of adjacent cars of a railway train, the flexibility of the hose enabling the adjacent cars to move relatively without interrupting the continuity 15 of the passage for the steam or air.

20 The object of the invention is to provide a hose for this use which possesses the requisite strength and flexibility, which may be manufactured at comparatively small cost, and which is constructed entirely of metal 25 so that rapid deterioration thereof under the influence of the fluid carried by the hose is avoided. These objects are attained by the provision of a hose having in its walls a plurality of annuli of thin, flat metal such 30 that the bending of these annuli permits flexure of the hose in any direction. These thin metal pieces supply all the flexibility required in a hose for use as an end-connector so that the employment of non-metallic parts which would be injuriously affected by the steam is avoided and the provision of pivotal joints in the hose formed to permit the passage of the fluid there-through is rendered unnecessary.

40 The preferred embodiment of my invention is illustrated in the accompanying drawings in which—

Figure 1 is a sectional elevation of the end-connectors, and Figs. 2 and 3 are transverse sections of the hose on lines 3—3 and 4—4 of Fig. 1, respectively.

50 Referring to these drawings, 4, 4 indicate the adjacent ends of the train pipes on two adjacent cars of a train, these being provided with downwardly-turned ends as shown, adapted to be connected by the flexible end-connectors provided with detachable couplings 6 at their free ends. The end-connectors are made entirely of metal so 55 that they will be well able to resist the action and strain thereon of the steam or com-

pressed air passing through them, and moreover, possess the amount of flexibility necessary for maintaining the passage for the steam or air throughout the relative 60 movement of the two cars of the train incident to movement of the train upon a curve and the compression and extension of the springs of the draft rigging.

The construction of the end-connectors is 65 illustrated in Figs. 1, 2 and 3. The end of each of the pipes 4 is turned downwardly as shown, and to this end of the pipe the connector is joined in any suitable manner, as by means of a sleeve 7 threaded into the end 70 of the pipe 4. From this sleeve the end-connector extends vertically downward and then laterally in a direction approaching the horizontal. The vertically disposed portion of the end-connector consists of a plurality 75 of tubular members 8, a plurality of rings 9 and 10 and a plurality of thin metallic annuli 11, each of the latter joining two of the tubular members and rings. Each of the tubular members 8 consists of a sleeve having 80 at one end an integral annular portion 12 lying in a plane substantially transverse to the axis of the hose and a flange 13 at the edge of the portion 12 extending a short distance in a direction parallel to the axis of 85 the hose. The face of the flange 13 on each of the members 8 is provided with a groove and in each of the ends of each of the sleeves 9 and 10 is a similar groove. Each of the thin metal annuli 11 is provided with a 90 flange 14 at its outer edge turned at substantially a right angle to the plane of the annulus and a flange 15 at its inner edge also turned at an angle substantially of ninety degrees to the plane of the annulus but in a 95 direction opposite to that in which flange 14 is turned. The flange 14 is secured in the groove in the face of the flange 13 on tubular member 8 in any suitable manner, as by means of solder, and the flange 15 is similarly secured in the groove in one end of the sleeve 9; at the other end of the sleeve 9 the flange 15 on the inner edge of a similar annulus 11 is secured in like manner in the groove in the sleeve. The flange at the 100 outer edge of this annulus and a flange at the outer edge of a similar annulus are secured in grooves in the opposite edges of a sleeve or ring 10 of larger diameter than sleeve 9. In this manner as many of the thin metallic 105 annuli as may be desired are secured between two of the tubular members 8, the

small sleeves 9 and the large sleeves or rings 10 being inserted between the adjacent annuli in order to unite them. The lower tubular member 8 is connected to a similar 5 tubular member by a metallic pipe 16 threaded at its ends, the length of this pipe being dependent upon the length desired for the completed end-connector. A plurality of the thin metal annuli 11 are also interposed 10 in like manner between this tubular member and a similar one in the manner above described.

A rigid metallic pipe 17 has one end connected by a suitable thread with the sleeve 15 of the lowest tubular member 8, this pipe having therein a bend, as shown, so that the major portion of it extends in a direction approaching the horizontal. At the free end of this pipe 17 is secured the 20 detachable coupling-member whereby the ends of two of the end-connectors are joined. The end-connector at the right of Fig. 1 is constructed in all respects like that on the left, above described.

25 The end-connectors are of such size that when the cars of a train are at the normal distance apart the portions thereof having the metallic annuli therein are vertically disposed. When the two cars move relatively for any reason as when they run upon a curve or when the springs of the draft rigging are compressed or extended, the vertically-disposed portions of the end-connectors will be flexed in whatever direction 30 may be necessary to allow for this movement of the cars while still maintaining the passage for the air or steam. This flexure is provided wholly by the thin metal annuli, each of which allows a small amount 35 of relative movement of the parts connected thereby and the sum of these relative movements being quite sufficient to make up the requisite flexibility of the connector. It 40 will be seen that since the hose is constructed

entirely of metal it will not be injuriously 45 affected by the fluid passing therethrough.

Having now described my invention, what I claim as new therein and desire to secure by Letters Patent is as follows:—

1. A flexible end-connector for a train-pipe consisting of a normally straight, flexible tubular metallic member adapted to be connected to and to extend vertically downwardly from the end of the train-pipe and having in its wall a plurality of annuli of 50 thin metal disposed in a plane substantially transverse to the axis of the member and adapted to flex to permit bending of the member, a rigid tubular metallic member connected to the lower end of said member 55 and bent intermediate its ends to extend laterally therefrom, and a detachable coupling on the free end of said last-named tubular member, substantially as set forth.

2. A flexible end-connector for a train-pipe consisting of a tubular metallic member adapted to be connected to and to extend downwardly from the end of the train-pipe, said member consisting of metallic sleeves, 60 substantially flat annuli of thin metal between said sleeves disposed substantially transverse to the axis of the member, and integral flanges on the edges of said annuli turned at an angle thereto and embedded 65 in grooves in the ends of said sleeves, a rigid tubular member connected to the lower end of said member and bent intermediate its ends to extend laterally therefrom, and a detachable coupling on the free end of said last-named member, substantially as set forth.

This specification signed and witnessed this 70 14th day of January, 1908.

EDWIN T. GREENFIELD.
